HANDKERCHIEF

Application filed July 2, 1929. Serial No. 375,545.

This invention relates to handkerchiefs and has for an object to provide a handkerchief with means for removably fastening a corner portion thereof to a support or to the wrist 5 for being conveniently carried without the necessity of having a pocket in which to carry it, and so that the handkerchief may be kept in a substantially un wrinkled condition.

A further object is to provide a handkerchief with means for removably fastening a corner portion thereof to a support or to the wrist so that the handkerchief may be conveniently carried and used or readily carried and gracefully draped over the arm 15 when not in use.

A still further object is to provide a handkerchief with fastening means of the above kind which will also permit fastening of the corner portion of the handkerchief to a necklace, girdle or the like worn by the user, whereby the handkerchief may, if desired, be draped through the necklace or girdle for being gracefully worn and conveniently carried without danger of loss or objectionable 25 wrinkling.

In the accompanying drawing:

Figure 1 is a side view illustrating the manner in which the handkerchief is attached to the user's wrist; and 30 Figure 2 is a plan view, drawn on a smaller scale, of the handkerchief shown in Figure 1 and embodying the present invention.

Referring in detail to the drawing, the handkerchief includes a fabric sheet or body 5 having attached to one edge portion or corner thereof one end of a short flexible strip or tape 6 having means to detachably connect the other or free end thereof to the attached end of the same. As shown, this connecting means preferably consists of a separable fastener such as used on gloves, one member 7 of which is attached to the free end of the strip or tape 6 and the other member 8 of which is secured to the attached end of said strip or tape. It is thus apparent that the edge or corner portion of the handkerchief to which the tape 6 is attached may be passed around the wrist and the tape 6 then passed and fastened around the portion of the handkerchief body 5 adjacent the wrist, as shown 50 in Figure 1. When this is done and the ends of the tape 6 are connected, the handkerchief is securely fastened to the wrist for being conveniently used and carried without danger of loss or objectionable wrinkling. 55 Moreover, the handkerchief, which is ornamental and especially suitable for evening wear, may be gracefully draped over the arm when not in use. It is obvious, however, that by fastening the tape around a necklace, or 60 girdle worn by the user, the handkerchief may be gracefully draped through the necklace or girdle and conveniently carried and kept in good shape.

The corners or spaced edge portions of the 65 body 5 are preferably provided with ornamental lace trimmings 9 provided with gathered border strips 10. At each of three of the corners of the body 5 a single trimming 9 may be used as a continuation of the 70 body 5 to form such corner, but at the remaining corner the body 5 is extended so as to provide a corner portion of relatively strong material to which an end of the tape 6 is attached, two trimmings 9 being attached respectively to opposite sides of the last named 75 corner portion so that uniform and enhanced ornamental appearance is had when the handkerchief is attached to the wrist or necklace. 80

What I claim is:

1. A handkerchief including a sheet of fabric, and a short tape attached to one corner portion of said sheet and provided with means to detachably connect the ends thereof, whereby the corner portion of the handkerchief may be passed around the wrist and the tape secured in loop formation around the sheet adjacent the wrist to secure the handkerchief to the wrist. 85

2. A handkerchief including a sheet of fabric, and a short tape attached to one corner portion of said sheet and provided with means to detachably connect the ends thereof, whereby the corner portion of the handkerchief may be passed around the wrist and the tape secured in loop formation around the sheet adjacent the wrist to secure the handkerchief to the wrist, ornamental trimmings attached to said sheet, the sheet be- 95 100

ing itself extended to form one edge portion thereof, said tape being attached to the last named edge portion of the sheet, and ornamental trimmings attached to opposite sides 5 of said last named corner portion of the sheet.
In testimony whereof I affix my signature.
